COMBINED SPEEDLIGHT AND POWER PACK

William E. Bounds, Hermosa Beach, Calif., assignor to
Limelite Corporation, Los Angeles, Calif., a corpora-
tion of California

Application October 24, 1955, Serial No. 38,525

Term of patent 14 years

(Cl. D61—1)

Figure 1 is a perspective view of the combined speedlight and power pack showing my new design; and

Figure 2 is a rear elevational view of the combined speedlight and power pack.

I claim:

The ornamental design for a combined speedlight and power pack, substantially as shown.
